UNITED STATES PATENT OFFICE.

THOMAS E. MURRAY AND GEORGE K. JESSUP, OF NEW YORK, N. Y.; SAID JESSUP
ASSIGNOR TO SAID MURRAY.

GLOW-LAMP FIXTURE.

1,135,541

Specification of Letters Patent. Patented Apr. 13, 1915.

Application filed March 28, 1914. Serial No. 827,859.

To all whom it may concern:

Be it known that we, THOMAS E. MURRAY and GEORGE K. JESSUP, citizens of the United States, residing at New York, in the county of New York and State of New York, have invented a certain new and useful Improvement in Glow-Lamp Fixtures, of which the following is a specification.

The invention is a glow-lamp fixture, and 10 comprises a solid block of insulating material, to one end of which is secured the threaded shell for the reception of the lamp, and at the other end are located the circuit terminals. Within a recess in the block is a 15 switch mechanism interposed between said circuit terminals and said shell.

The invention consists in the construction more particularly pointed out in the claims.

In the accompanying drawings—Figure 1 20 is a cross section of our socket on the line z, z of Fig. 4, Fig. 2 is an elevation, Fig. 3 is a top view showing the construction of the circuit terminals, and Fig. 4 is a section on the line z, z of Fig. 1.

25 The socket comprises a cylindrical body J of insulating material, to which is secured the usual threaded metal sleeve K for the reception of a glow-lamp. On the upper side of body J is a circular recess, in which is disposed an arc-shaped metal plate L which is electrically connected to sleeve K by two bolts M which pass through the body J the usual disks of insulating material interposed between said body and sleeve K , and enter 30 the metal of sleeve K . Also in said recess is a plate N secured by screw O , which is bent to pass through a notch in the edge of the socket and to extend below the top surface of a transverse opening in said body. 35 Within said opening is the metal plate P which receives the threaded end of the shank of a central contact disk Q within sleeve K . Said disk and shank are insulated, as usual, from said sleeve by disks of insulating material within the sleeve and a bushing of similar material inclosing said shank. The 40 ends of plate P are upwardly turned, one end having a vertical slot R to receive the end of the switch shaft S , and the other end having a notch T also receiving said shaft. Said shaft carries the metal switch cam U , 45 which bears against the bent over leaf spring V electrically connected to plate P . The leading-in wire H is secured to plate N by

binding screw W . The leading-in wire I is 55 secured to plate L by binding screw X .

When the switch key is turned in the position shown in Fig. 1, circuit is established through cam U , from plate N , to disk Q . When the switch key is turned in the position shown in Fig. 2, contact is interrupted between cam U and plate N .

The connections on the socket for the leading-in wires, namely, plates L and N , are on the top of the socket, so that the leading-in 65 wires may pass directly from said plates to and through the sleeve Y , thus avoiding any openings for said leading-in wires in the sides of the socket or the necessity of carrying such wires between socket and shell in 70 order to make the connections. So also when the parts of the shell are separated, said plates L and N on top of the socket are exposed and at once accessible, thus permitting the leading-in wires to be readily connected. 75

We claim:

1. A glow-lamp fixture, comprising a block of insulating material having a transverse recess, a threaded shell lamp socket secured upon one end of said block, a central contact in said threaded shell, circuit terminals on the opposite end of said block, circuit connections between said circuit terminals respectively and said shell and said central contact therein, and a switch mechanism in said recess and interposed in the connection between a circuit terminal and said central contact. 80

2. A glow-lamp fixture, comprising a block of insulating material, having a transverse recess extending through it, a threaded shell lamp socket secured upon one end of said block, a central contact in said shell, circuit terminals on the opposite end of said block, a connection extending from one of said terminals through the material of said block to said threaded shell, a connection extending from the other of said terminals to a contact plate in said recess, a second contact in said recess, a connection between said second contact and the central contact in said shell, and a rotary switch key in said recess co-operating with the contacts therein. 95

3. A glow-lamp fixture, comprising a block of insulating material, having a transverse recess extending through it, two circuit terminals on one end of said block, one of

- said terminals entering said recess, a threaded shell lamp socket on the opposite end of said block, a central contact in said shell, a conducting rod extending through the material 5 of said block and connecting the other of said terminals to the shell of said socket, a metal bracket seated in said recess and connected to the center terminal of said socket, a leaf spring in said bracket, a connection 10 between said leaf spring and the central contact of said shell, and a rotatable switch key journaled in said bracket and coöperating with said first-named circuit terminal and said leaf spring.
- 15 4. A glow-lamp fixture, comprising a block of insulating material, having a transverse opening extending through it, two circuit terminals on one end of said block, one of said circuit terminals being a bifurcated 20 plate having its loop received in a notch in

one side of said block above said recess, a metal bracket in the bottom of said recess, a threaded shell lamp socket, a central contact in said shell, a connection extending through the material of said block from said central 25 contact to said bracket, a spring contact on said bracket, a connection extending through the material of said block from said shell to the other of said circuit terminals, and a switch mechanism disposed in said recess and interposed between said spring and said bifurcated plate.

In testimony whereof we have affixed our signatures in presence of two witnesses.

THOMAS E. MURRAY.
GEORGE K. JESSUP.
